BOWL-HOLDER FOR MELTED SOLDER

Roy McClarkey, Valley, Nebr.

Application April 8, 1933. Serial No. 665,162

3 Claims. (Cl. 294—27)

The invention relates to a holder for solder bowls, and has for its object to provide a support for use while the bowl contains melted solder, or which contains a liquid which might cause injury to workmen if accidentally overturned or spilled.

In the use of solder bowls, after the solder has been melted, it is often necessary that the bowl with its contents be carried to the place where repairs are to be made, this being true in the work of plumbing, installation of machinery or when stationary objects are to be repaired. One of the objects, therefore, is to provide an attachment or support for the bowl which may be readily applied thereto and removed therefrom, and including a handle, said support or attachment being such that the bowl may be maintained in a horizontal position, remote from the handle, while carried about, and that personal injuries may be avoided.

Also, during the work of repairing telephone and telegraph lines which are supported above the ground upon the crossarms of telegraph poles it is necessary to elevate the bowls with the melted solder to the linemen for use in making repairs, a cord and pulley generally being used for this purpose, and therefore the device is of such construction that the bowl and its contents will be maintained in a horizontal position and will not become overturned by accidental means.

While the device may be used to advantage by plumbers, and used by linemen when repairing electrical conductors, as mentioned, it may be used to equal advantage as a safety appliance in the movement and handling of acids and various kinds of liquids.

With the foregoing objects in view and others to be mentioned herein, the invention presents a new and useful construction, combination and arrangement of parts as described and claimed and as illustrated in the accompanying drawing, it being understood that changes may be made in form, size, proportion of parts and minor details, said changes being within the scope of the invention as claimed.

In the drawing, Fig. 1 is a side view of the device applied to a receptacle for elevating or lowering it.

Fig. 2 is a side view showing the device in an inverted position for manually supporting the receptacle.

Fig. 3 is a plan view showing a terminal part, 55 of spiral form, for one of the arms of the de-

vice and which operates as a holder for the bail of the receptacle, the view being a section through said arm on line 3—3 of Fig. 1.

Fig. 4 is a plan view of a combined brace and detent-bar, being a terminal part of the second 60 arm of the device, said view being on line 4—4 of Fig. 2.

Referring now to the drawing for a more particular description, the invention is described and illustrated in connection with a receptacle 65 or soldering bowl 5 provided with a bail 6 and a cord or cable 7, said cord being used in the operation of elevating the bowl while containing melted solder, and used while lowering said bowl.

The device consists of a single strip, preferably of metal, bent to provide a handle 8 and a pair of end-portions or intersecting arms 9 and 10, one of said arms, at the intersection, preferably being wound around the other arm as indicated at 11 to provide a strong construction, said arm 9, outwardly of said intersection, being formed as a hook 12 of spiral shape for a removable mounting on the bail 6 of the bowl. The arm 10, outwardly of said intersection is provided with a U-shaped supporting-member or hook 13 for receiving a loop 14 of the cord 7, and outwardly of the hook or U-shaped part 13 is a terminal shoe or contact-piece 15 for engaging the side of the receptacle when the parts 85 are disposed as shown in Fig. 2 of the drawing. Therefore, that part of arm 10 outwardly of said intersection, operates as a brace-bar.

In operation, for hoisting or elevating the bowl or receptacle, the parts are disposed approximately as shown in Fig. 1, the loop 14 of the cord being mounted on the hook 13, and during the work of repairing telegraph or telephone wires, the workman may place the hook 13 upon any suitable support.

The advantage in the use of the hook 12 of spiral shape is the fact that it prevents accidental disengagement thereof from the bail 6, and tends to prevent any swinging movement of the bail and bowl 5 in one direction. The shoe 15 consists of a curved bar, its curvature corresponding to the curvature of the side wall of the bowl, so that it may suitably engage the bowl, said shoe or bar 15 being disposed approximately at right-angles to the adjacent portion of the arm 10, and it will be understood that this shoe or bar operates as a detent to prevent the device from becoming detached from the loop 14 of the cable.

For instance, during the upward movement of

the bowl by use of the cord or cable 7, if the handle 8 should accidentally encounter some obstruction it would be swung downwardly, the result being that the loop 14 might become detached and slide outwardly from the hook 13, but in that event the loop 14 would become caught upon the bar or shoe 15 to prevent overturning or any mishap to the bowl or its contents, and this is one of the functions to be 10 discharged by the shoe or bar 15.

Fig. 2 illustrates the device for use when it is required that the bowl and its contents shall be manually moved about, and it will be seen that each part of the device discharges a function, the handle at this time being disposed outwardly of a side of the bowl, and the bail of the bowl being disposed in a horizontal position, approximately parallel with the arm 9, the shoe 15 engaging the side of the bowl and, 15 together with that part of the arm 10 outwardly of the intersection 11, operating as a brace, and thereby the shoe 15 discharges a 20 second function.

It has been found that the device is of great 25 advantage when used as illustrated in Fig. 2 since the handle is disposed in a position remote from the bowl, and the latter may be conveniently supported while disposed in positions of 30 advantage during the operation of soldering. Numeral 16 indicates a jacket or cover for the handle, this covering consisting of any suitable material to operate, preferably, as a non-conductor of heat and electricity.

The loop 11 at the intersection of the arms 35 9 and 10 may be dispensed with provided the metallic strip mentioned has adequate strength

for practical purposes, it being necessary, of course, that the device should be of rigid construction since the receptacle or bowl and its contents may have a considerable weight.

I claim as my invention,—

1. In a holder for the purposes described, a metallic strip bent between its ends to provide a handle and a pair of intersecting arms, one of said arms being provided outwardly of said intersection with a hook, the other arm of 85 said pair being provided at its terminal, transversely thereof, with a shoe having a longitudinal curvature, said last named arm being bent to provide a supporting-member between said intersection and said shoe.

2. In a holder for the purposes described, a metallic strip bent to provide a handle and a pair of intersecting arms, one of said arms outwardly of said intersection being provided with a hook of spiral form, the other arm of said 95 pair being provided at its terminal, transversely thereof, with a shoe, and provided between said intersection and said shoe with a curved supporting-member.

3. In a holder for the purposes described, a metallic strip, bent adjacent to its ends to provide a handle and a pair of arms intersecting and connected with each other intermediate their ends and said handle, one of said arms being provided at its end with a hook of spiral 105 form, the other arm of said pair being provided at its end with a shoe and having a part approximately of U-shape to operate as support between said shoe and said intersection.
